CLAIM

We claim, the ornamental design for a confection, as shown and described.

DESCRIPTION

FIG. 1 is a top, right side perspective view of a confection showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The evenly-spaced broken lines in FIGS. 1-3 and 6-7 illustrate portions of the confection that form no part of the claimed design. The dash-dot-dash broken lines in FIGS. 1-7 illustrate the boundary of the claimed design which forms no part thereof.
